DESIGN FOR A TOURIST CABIN

John P. Larkin, Larned, Kans.

Application December 4, 1940, Serial No. 97,069

Term of patent 14 years

To all whom it may concern:

Be it known that I, John P. Larkin, a citizen of the United States, residing at Larned, in the county of Pawnee and State of Kansas, have invented a new, original, and ornamental Design for a Tourist Cabin, of which the following is a specification, reference being had to the accompanying drawing, forming part thereof.

Fig. 1 is a front elevation of a tourist cabin, showing my new design.

Fig. 2 is a rear elevation of Fig. 1.

Fig. 3 is an end elevation of Fig. 1.

I claim:

The ornamental design for a tourist cabin, substantially as shown.

JOHN P. LARKIN.
